UNITED STATES PATENT OFFICE

113,859

DESIGN FOR A COMBINED BRACELET AND MEMO PAD

Kenneth Van Cott, New York, N. Y.

Application February 7, 1939, Serial No. 82,841

Term of patent 3½ years

To all whom it may concern:

Be it known that I, Kenneth Van Cott, a citizen of the United States of America, residing in New York city, in the Borough of Manhattan, county and State of New York, have invented a new, original, and ornamental Design for a Combined Bracelet and Memo Pad, of which the following is a specification, reference being had to the accompanying drawing, forming part thereof, wherein

I claim:

The ornamental design for a combined bracelet and memo pad, substantially as shown.

KENNETH VAN COTT.
